UNITED STATES PATENT OFFICE.

BENEDICT O. SIEGFUS, OF SALT LAKE CITY, UTAH.

BEET-HARVESTER.

1,179,767.

Specification of Letters Patent. Patented Apr. 18, 1916.

Application filed July 7, 1915. Serial No. 38,460.

To all whom it may concern:

Be it known that I, BENEDICT O. SIEGFUS, a citizen of the United States, residing at Salt Lake City, in the county of Salt Lake 5 and State of Utah, have invented new and useful Improvements in Beet-Harvesters, of which the following is a specification.

This invention relates to beet harvesters, and it has particular reference to a machine 10 which by a single operation will pull or lift the beets from the ground and detach the tops from the same.

One object of the present invention is to produce a machine of simple and effective 15 construction embodying a ground engaging wheel supported for rotation and having means for grasping the tops of the beets, the beets being lifted from the ground as the wheel revolves, means being provided 20 for severing the beets from the tops and for conveying the latter to a box or receptacle.

A further object of the invention is to simplify and improve the construction of the rotary pulling element and related parts 25 including the means for causing the said pulling element to release the tops at the proper point.

With these and other ends in view which will readily appear as the nature of the 30 invention is better understood, the same consists in the improved construction and novel arrangement and combination of parts which will be hereinafter fully described and particularly pointed out in the claims.

In the accompanying drawings has been 35 illustrated a simple and preferred form of the invention, it being, however, understood that no limitation is necessarily made to the precise structural details therein exhibited, but that changes, alterations and modifications within the scope of the claims may 40 be resorted to when desired.

In the drawings,—Figure 1 is a side elevation of a machine constructed in accordance with the invention, the inner wheel being removed. Fig. 2 is a top plan view of the machine. Fig. 3 is a rear elevation. Fig. 4 is a horizontal sectional view taken through the rotary pulling wheel substantially on the line 4—4 in Fig. 1. Fig. 5 is a sectional detail view, enlarged, taken on the line 5—5 in Fig. 1. Fig. 6 is a sectional detail view, enlarged, taken on the line 6—6 in Fig. 1. Fig. 7 is a perspective detail view of a portion of the rim of the pulling wheel. Fig. 8 is a perspective detail view

of one of the rim sections of the pulling wheel.

Corresponding parts in the several figures are denoted by like characters of reference. 60

The carrying frame of the improved machine comprises forwardly convergent side members or hounds 15 between the forward ends of which a tongue 16 is mounted, the rearward ends of said hounds being provided with bearings for the axle 17 which is supported by the ground wheels 18.

The pulling wheel comprises in its construction a sleeve or hub member 19 which is loosely mounted on the axle 17, the bore 70 of said sleeve or hub being of a diameter materially exceeding that of the axle so that said hub and the parts connected therewith will not only be free to revolve, but also to move upward, downward, forward and rearward with respect to the axle, thereby permitting said pulling wheel to adapt itself to irregularities in the surface of the ground. The diameter of the pulling wheel is less than that of the transporting wheels, 75 so that the pulling wheel will ride upon the ridge in which the beets are growing, while the ground wheels will ride in the hollows between the ridges. The sleeve or hub 19 is provided at the ends thereof with flanges 80

20, and intermediate said flanges the hub is provided with two circumferential series of radially extending arms 21 with which spokes 22 are pivotally connected by pins or pivot members 23 so that the spokes will 90 be capable of swinging toward and apart from each other. The hub is confined between disks 20' that are secured on the axle, said disks serving to prevent endwise or longitudinal movement of the hub with respect to the axle while in no wise interfering with upward, downward, forward and rearward movement, as previously set forth.

The outer ends of the spokes of each series are connected together by segment plates 100 24 made preferably of sheet metal, said segment plates being provided at their outer edges with ground engaging flanges 25. The ends of the segment plates are loosely connected with the spokes by means of hinge 105 joints 26 of suitable construction so that the individual spokes will be free to rock on their respective pivots 23. Bolted or otherwise secured on the opposed inner faces of the segment plates 24 are annular cushions 110 27 of resilient material, such as rubber, or a composition containing rubber. While

these cushions are described as being "annular" in the sense that they extend entirely around the circumference of the pulling wheel, it is to be understood that each cushion may be made up of a plurality of sections when desired. The cushions 27 are provided in their opposed faces with circumferential grooves 28, whereby they will be enabled to take a better hold on the tops 10 of the beets, as will be hereinafter more fully set forth.

The flanges 20 at the ends of the hub are provided with annular grooves 29 for the reception of frames F, each of said frames 15 consisting of a ring 30 having a plurality of radially extending arms 31, 32, 33. The arms 32 extend forwardly and are terminally connected with a rod 34 which is slidably mounted in longitudinal slots 35 in the 20 hounds or frame bars 15. The arms 33 extend rearwardly and with said arms is adjustably connected a yoke 36 by means of bolts 37 engaging slots 38 in the arms 33. It will be seen that while the frame F, including the hub, is free to rise and fall and to move forward and backward with respect to the axle 17, said frame is prevented from 25 rotating by the connection of the arms 32 with the rod 34. The arms 31, as stated, 30 extend radially with respect to the ring 30, said arms being of substantially equal length and shorter than the arms 32, 33. The arms 31, 32, 33 serve to support the guide rings or track rings 39, said rings or track members 35 being connected with the arms of the frames F by means of bolts 40 about which springs 41 are coiled whereby the rings or track members are normally forced in the direction of the outer faces of the spokes 22, 40 which latter are equipped with anti-friction members, such as rollers 42, that ride in the rings or track members. The two sets or series of spokes will thus be forced resiliently in the direction of each other so as to 45 exert a gripping action on the tops of the beets engaged thereby, as will be hereafter more fully described.

For the purpose of gathering and bunching the tops of the beets together so as to 50 enter between the annular cushions 27 between which the tops will be grasped and held securely, there is provided a pair of guide members 43, said guide members being made of sheet metal or other material and 55 provided with forwardly divergent opposed edges 44 between which the beet tops will enter. The members 43 may be supported entirely or in part by the arcuate guides 45, which latter are supported by a rod or bar 60 60 having at its rearward end an eye 47 engaging the hub 19, the forward end of the bar 46 being connected with the rod 34 by means of an eye 48 engaging said rod. The bar 46 is provided with laterally extending 65 arms 49 with which the guides 45 are con-

nected, said guides approximately concentric with the hub 19 and arranged contiguous to the inner faces of the spokes 22, the rollers of which, 42, will engage said guides. At their upper ends the guides 45 are relatively close together, but they diverge downwardly to a point 50 which is the point at which the beet tops are received by the pulling wheel. At the point 50 the guides 45 may terminate abruptly, or they may be 75 provided with convergent tail portions 51 to prevent the gripping action of the pulling wheel from being exerted too suddenly. It is obvious that when the pulling wheel is in operation, and the spokes reach the upper 80 portions of the guides 45, the said spokes will thereby be forced outwardly against the tension of the springs 41, thereby spreading the parts of the cushions 27 carried by said spokes apart from each other to facilitate 85 the entrance therebetween of the tops of the beets. As soon as said tops are positioned well between the cushions the spokes pass out of engagement with the guides 45, and the parts of the cushions carried thereby 90 will be forced in the direction of each other, thereby gripping the beet tops, as will be readily understood.

The frame members 15 support a downwardly extending bracket 53 with which the front end of a plow beam 54 is pivotally and adjustably connected by means of a pin or bolt 55. The beam is provided with a standard 56 carrying a small plow 57 which is suitably constructed to loosen the soil and to exert a lifting action on the beets encountered thereby, the purpose of said plow being not to form a furrow, but simply to assist in lifting or pushing the beets from the ground. For the purpose of lifting the 100 plow from the ground and supporting it in a raised position for transportation, means are provided including a hand lever 58 secured to a rock shaft 59 having a crank or arm 60 which is connected by a rod or link 61 with one arm 62 of a bell crank fulcrumed on the axle 17, the other arm 63 of said bell crank being connected by a rod or link 64 with the plow beam 54 which may thus be raised or lowered. The hand lever 58 is provided 110 with a stop member 65 engaging a rack segment 66 for the purpose of maintaining the parts securely in adjusted position.

The yoke 36 carries a knife or cutting member 67 that lies adjacent to the circumference of the pulling wheel for the purpose of severing the beets from the tops as they are being carried past said knife. A seat 68 for the driver or operator is supported on the frame of the machine.

Supported between the guide members 45 is a slide or chute 69 which is adapted to receive the beet tops as they are being released from the pulling wheel by the spreading of the spokes caused by the guides 45. Over 125 130

said slide or chute the beet tops are conveyed into a box or receptacle 70 which may be permanently or detachably connected with the frame members 15 in any convenient manner.

In the operation of this machine it will be seen that the pulling wheel will be rotated by contact with the ground of the flanges or shoes 25 of the plates 24 whereby the spokes are linked together, the wheel adapting itself freely to irregularities in the ground, owing to its being loosely mounted on the axle in the manner described. The down-going spokes on the forward side of the machine will be gradually spread apart or diverged by the action of the guides 45, and the cushions or gripping members 27 will thus be widely spread apart at the point where the beet tops enter therebetween, the beet tops being bunched by the guide members 43. Shortly after the beet tops enter between the cushions or gripping members 27 the spokes will pass out of engagement with the guides 45, and said spokes will now be forced in the direction of each other by the action of the springs 41, causing the tops of the beets to be gripped firmly between the cushions 27. At this point the action of the plow 57 will loosen the soil about the beet, and the plow will exert an upwardly pushing action on the beet root, causing the latter to be readily extracted and carried upward by the up-going rearward portion of the pulling wheel until the knife 67 is encountered, whereby the beet is severed and caused to drop on the ground in a position from which it may be subsequently gathered. The tops are carried upward and forward by the wheel until the upper ends of the guides 45 are encountered, when the cushions 27 will be forced apart, thereby releasing the tops which will now be discharged over the slide or chute 69 into the box 70.

As will be seen from the foregoing description the operation of the pulling wheel is continuous, the beets being extracted and severed from the tops while the latter are carried to a place of deposit. It is obvious that a suitable box or receptacle may be arranged for the reception of the beets when desired. It is also to be understood that while in the accompanying drawings only a single pulling wheel has been shown, a machine might be constructed embodying the principle of this invention and equipped with a plurality of pulling wheels to operate simultaneously on a plurality of rows of beets.

The improved machine is very simple in construction and operation; it is light and durable, and may be constructed at a very moderate expense. The parts of the device are to a large extent adjustable and interchangeable, and the parts may be easily

replaced at small expense when broken or injured. The machine may be operated with slight expenditure of power; the work of the machine is performed without injury to the beets or the tops, and the machine is readily adapted to operate on all sizes of beets and any kind of soil.

It is desired to state that the guide rings or track rings 39, which are constructed of non-resilient material, are to be properly shaped to cause the moving parts of the pulling wheel to be properly guided thereby to exercise gripping and releasing action with respect to the beet tops at the proper times.

Having thus described the invention, what is claimed as new, is:—

1. In a machine of the class described, the combination with a frame having a wheel carrying axle, of a ground engaging pulling wheel having a hub mounted on the axle, the diameter of the bore of said hub being materially larger than the diameter of the axle to permit the wheel to adjust itself to irregularities in the ground irrespective of the axle.

2. In a machine of the class described, a ground engaging pulling wheel having flexible rims constituting gripping members, and means for forcing said rims resiliently in the direction of each other, said rims being provided with annularly grooved gripping cushions on their opposed faces.

3. In a machine of the class described, a ground engaging pulling wheel having flexible rims constituting gripping members and means for forcing said rims resiliently in the direction of each other, said rims comprising each a plurality of segment plates having ground engaging flanges.

4. In a machine of the class described, a ground engaging pulling wheel comprising a hub having two circumferential series of radial arms, spokes pivotally connected with the arms, rims comprising segment plates hingedly connected with the spokes and constituting flexible rims, and means for forcing said flexible rims resiliently in the direction of each other.

5. In a machine of the class described, the combination with a main frame having a wheel carrying axle, of a ground engaging pulling wheel supported on the axle and including a hub having a bore of materially larger diameter than the axle, said hub having terminal annular grooved flanges and two circumferential series of radial arms intermediate the flanges, spokes pivotally connected with the arms, flexible rims consisting of segment plates hingedly connected with the spokes, guide frames mounted in the annular grooves of the flanges, said guide frames having radial arms, a rod carried by the main frame and connected with some of said arms to prevent rotation.

- of the guide frames, guide rings carried by the arms of the guide frames, and springs whereby said guide rings are forced in the direction of the spokes to force said spokes and the rims carried thereby yieldingly in the direction of each other.
6. In a machine of the class described, a wheel supported carrying frame having an axle and side members provided with longitudinal slots, in combination with a ground engaging pulling wheel having a hub mounted on the axle, the hub having a bore of materially larger diameter than the axle to permit the pulling wheel to adapt itself to irregularities in the surface of the ground irrespective of the wheel supported frame, said pulling wheel including two sets of pivoted spokes, flexible gripping rims carried by said spokes, means for forcing the gripping rims resiliently in the direction of each other including guide frames mounted on the hub and having radial arms, a rod supported in the longitudinal slots in the side members of the main frame and connected with some of the arms of the guide frames to prevent rotation of the latter, and guide rings carried by the arms of the guide frames and forced resiliently against the two sets of spokes, said spokes being provided with rollers to engage said guide frames.
7. In a machine of the class described, a wheel supported carrying frame having an axle and side members provided with longitudinal slots, in combination with a ground engaging pulling wheel having a hub mounted on the axle, the hub having a bore of materially larger diameter than the axle to permit the pulling wheel to adapt itself to irregularities in the surface of the ground irrespective of the wheel supported frame, said pulling wheel including two sets of pivoted spokes, flexible gripping rims carried by said spokes, means for forcing the gripping rims resiliently in the direction of each other including guide frames mounted on the hub and having radial arms, a rod supported in the longitudinal slots in the side members of the main frame and connected with some of the arms of the guide frames to prevent rotation of the latter, and guide rings carried by the arms of the guide frames and forced resiliently against the two sets of spokes, said spokes being provided with rollers to engage said guide frames; some of the arms of the guide frames being extended rearwardly, and a knife carrying yoke connected adjustably with said rearwardly extending arms.
8. In a machine of the class described, a wheel supported main frame having an axle, a ground engaging pulling wheel loosely mounted on the axle to adapt itself to irregularities in the ground, said pulling wheel having pivoted spokes and flexible gripping rims and means for resiliently forcing said rims in the direction of each other, a rod movably supported by the main frame, a bar having terminal eyes engaging said rod and the hub of the pulling wheel, spreading members carried by said bar and engaging the spokes to force the latter and the flexible rims apart from each other, and bunching members to gather the tops of beets and to guide them between the flexible rims while thus forced apart.
9. In a machine of the class described, a wheel supported main frame having an axle, a ground engaging pulling wheel loosely mounted on the axle to adapt itself to irregularities in the ground, said pulling wheel having pivoted spokes and flexible gripping rims and means for resiliently forcing said rims in the direction of each other, a rod movably supported by the main frame, a bar having terminal eyes engaging said rod and the hub of the pulling wheel, spreading members carried by said bar and engaging the spokes to force the latter and the flexible rims apart from each other, and bunching members to gather the tops of beets and to guide them between the flexible rims while thus forced apart, in combination with means for severing the beets from the tops, and a chute interposed between the spreading members to convey the tops to a place of deposit.
10. In a machine of the class described, a wheel supported main frame having an axle, a ground engaging pulling wheel loosely mounted on the axle to adapt itself to irregularities in the ground, said pulling wheel having pivoted spokes and flexible gripping rims and means for resiliently forcing said rims in the direction of each other, a rod movably supported by the main frame, a bar having terminal eyes engaging said rod and the hub of the pulling wheel, spreading members carried by said bar and engaging the spokes to force the latter and the flexible rims apart from each other, and bunching members to gather the tops of beets and to guide them between the flexible rims while thus forced apart, in combination with means for severing the beets from the tops, and a chute interposed between the spreading members to convey the tops to a place of deposit.
11. In a machine of the class described, a wheel supported main frame having an axle, a ground engaging pulling wheel loosely mounted on the axle to adapt itself to irregularities in the ground, said pulling wheel having pivoted spokes and flexible gripping rims and means for resiliently forcing said rims in the direction of each other, a rod movably supported by the main frame, a bar having terminal eyes engaging said rod and the hub of the pulling wheel, spreading members carried by said bar and engaging the spokes to force the latter and the flexible rims apart from each other, and bunching members to gather the tops of beets and to guide them between the flexible rims while thus forced apart, in combination with means for severing the beets from the tops, a chute interposed between the spreading members to convey the tops to a place of deposit, and a plow carried by the main frame to assist in loosening the soil and in pushing the beets from the ground.
